UNITED STATES PATENT OFFICE

169,946

WHEEL COVER

Frederic P. Plotkin, Los Angeles, Calif.

Application September 15, 1952, Serial No. 21,481

Term of patent 14 years

(Cl. D14—30)

To all whom it may concern:

Be it known that I, Frederic P. Plotkin, a citizen of the United States, residing at Los Angeles 34, Los Angeles County, State of California, have invented a new, original, and ornamental Design for a Wheel Cover, of which the following is a specification, reference being had to the accompanying drawing, forming part thereof.

Fig. 1 is a front view of a wheel cover showing my new design; and

Fig. 2 is a cross-sectional view taken along the line 2—2 of Fig. 1.

The dotted lines on the drawing are for illustrative purposes only.

I claim:

The ornamental design for a wheel cover, substantially as shown and described.

FREDERIC P. PLOTKIN.
